UNITED STATES PATENT OFFICE.

WILLIAM C. HIERING, OF NEWARK, NEW JERSEY, ASSIGNOR TO J. E. MEROOTT CO.,
OF NEWARK, NEW JERSEY, A CORPORATION OF DELAWARE.

CARD CONTAINER AND DESK TRAY.

Application filed October 3, 1925. Serial No. 60,197.

This invention relates to combined card containers and desk trays as used in connection with business office desks, and the like, and has as one of its objects to provide a device in which a plurality of cards may be contained, such for instance as a pack of playing cards, telephone, address, account or data cards, the same being normally enclosed in an essentially dust proof casing and, which upon opening the cover, are automatically raised into position for inspection or withdrawal.

It is a further feature to produce means for securing the card receptacle when in a raised position, thereby preventing its premature descent, but permitting it to yield upon closing the cover.

Another aim is in the provision of a fixed tray at the lower front part of the structure to receive pencils, pens and like objects of common use in position of instant access, the tray being so arranged with reference to the front wall of the casing as to support a single card therebetween, as a score or index card.

A still further object is to provide a firm and rigid metallic device of highly pleasing appearance, simple construction and adapted, in addition to the foregoing features, to be used as a high grade advertising medium, the front panel and cover presenting flat spaces of considerable area to be utilized for such purposes.

These several practical features are accomplished by the novel design, construction and assembly of parts hereinafter described and shown in the associated drawing, in which:—

Fig. 1 is an expanded perspective view showing in detail the several parts constituting the casing and tray of an embodiment of the invention.

Fig. 2 is a transverse sectional view taken at the center of the device as assembled, the cover and card container being shown in a raised position by full lines and in closed position by broken lines.

Figure 3 is an enlarged fragmentary view of the upper edge of the box, shown in Figure 1, to show the thickness of the box material.

The simplicity of the structure is obvious from inspection of the drawing, wherein may be seen the firm interlocking of the

several members by means of lugs which take the place of solder, screws or the like fastening means.

The base 5 consists of a flat rectangular plate, sheared and bent at its end and front to produce an ornamental pedestal molding 6, having inreaching bottom edges 7.

In order to stiffen the plate 5 one or more longitudinal ribs 8 are formed by pressing the metal between dies, and at the ends are transverse downwardly offset seats 9.

Carried on the seats 9 are opposed end brackets 10 having inreaching flanges at their ends and concave upper surfaces 11, from the central portion of the inner edges of which are downwardly extending prongs 12, pairs of similar prongs 13 reaching downward from the outer faces of the brackets.

The prongs 13 are suited to enter corresponding openings 13' in the forward portion of the seats 9 to be bent over and clinched, as shown in Fig. 2, holding the brackets rigidly to the base.

A tray 14 extends lengthwise between the brackets, to which it is secured by passing the prongs 12 through openings 12' in the ends of the concave portion of the tray and held by bending the ends of the prongs.

The tray 14 has a straight front wall 15 and a similar but higher rear wall 16, each of which are provided with prongs 17 and 18 respectively, to pass through openings 17' and 18' in the base plate 5 to be clinched therebelow, firmly fixing the tray to the base.

Rearward of the tray is an oblong rectangular casing composed of a rear wall 19, side walls 20 and partial front walls 21, of lesser height than the rear wall, which is provided at its bottom edge with prongs 22 to pass through openings 22' in the base.

Fixed to the inner surfaces of the narrow front walls 21 are upright cleats or strips 23 and removably engaged to the inreaching portions of these cleats is a main front plate or panel 24 flush and level with the front wall elements 21 and provided at its lower edge with prongs 25 to be fixed in the base plate openings 25'.

While it is obvious that the casing might be made of a single piece of material, it is preferred to make the panel 24 separate, as this element is adapted to bear imprints for

advertising purposes and therefore is interchangeable with other panels bearing unlike inscriptions.

Attached to the upper edge of the rear wall 19 is a longitudinally extending hinge 26 connecting a cover 27 having down-turned flanged edges 28 and 29 respectively at the ends and front, to engage over the end and front walls of the casing, the end walls of which contain recesses 30, covered by extensions 31 of the cover end flanges 28.

A card container, comprising a bottom wall or flooring 32, ends 33 and front and rear walls respectively 34 and 35, is freely 15 slidable up and down within the casing, the front wall 34 being sheared to spring outwardly, clearing the cleats 23 to make frictional contact with the panel 24 of the casing.

The rear wall 35 is provided with a small 20 circular opening 36, at the center, near its upper edge, this opening being receptive of a protuberance 37 pressed inwardly from the casing rear wall 19, which is further provided with a stop 38, partially sheared and 25 pressed inwardly, to limit the rise of the card container by reason of its rear edge making contact with the stop, at which time the protuberant detent 37 will have engaged the opening 36, maintaining the container in a raised position until force is applied to release the same.

The end walls 33 of the container are extended at the center and bent to present offset lugs 39, connected by links 40 with the 35 cover flanged extensions 31, these connections being made by rivets 41 acting as pivots on which the links freely operate.

It will now be apparent that when the cover is open, as shown in full lines in Fig. 2, 40 the container will be raised to its highest point, against the stop 38, limiting the movement of the cover, due to the action of the detent 37.

However, upon applying moderate force to 45 the cover, in closing the same, the detent becomes released and the card container, with its contents, X, moves into the broken line position indicated, in which the casing is substantially dust tight.

As the rear wall 16 of the fixed tray is 50 separated by a narrow space 42, from the front wall of the casing, a thin object, as a score or title card as at X, may be inserted and retained positionally therein; it will 55 also be noted that the inclined position of the cover when closed provides a convenient supporting surface for making card and like notations.

From the foregoing it will be seen that a 60 simple structure composed of a small number of parts has been disclosed and that the same is essentially rigid and servicable.

While certain preferred embodiments of 65 this device have been shown and described, it will be understood that changes in the

form, arrangements, proportions, sizes and details thereof may be made without departing from the scope of the invention as defined in the appended claims.

Having thus described my invention, what 70 I claim as new and desire to secure by Letters Patent is;

1. A desk appliance comprising a hollow elongated rectangular base, a tray rigidly fixed on the level front portion of said base, a casing narrowly spaced rearward of said tray and fixed to said base, said casing having an inclined top, and a flanged cover hinged to the rear wall of said casing to fold over the top thereof forming a dust 75 proof closure.

2. A desk appliance comprising a low flat sheet metal base, a tray fixed on the front thereof, a casing at the rear presenting a card receiving space therebetween, said casing having a top inclined 80 downwardly towards the front, a dust tight cover hinged to said casing, and an advertising panel removably engaged at the front 85 of said casing.

3. A desk appliance comprising a hollow sheet metal base having a level top, a tray fixed on the front thereof, a casing at the rear having an inclined top, a flanged cover hinged to the rear wall of said casing to 90 fold thereover, means to limit the opening of said cover, and a removable panel at the front of said casing.

4. A desk appliance comprising a base, a casing fixed thereon, a cover hingedly engaged on said casing, a card container movable up and down in said casing, said container having a level horizontal bottom and four perpendicular walls, one of said walls having an opening, links operatively connecting the cover and the container, and a protuberance on said casing operative as a frictional drag on said container, said protuberance engaging the mentioned opening to retain the container when in a raised 100 position.

5. A desk appliance comprising a base, a casing fixed thereon, a cover hingedly engaged on said casing, a card container movable up and down in said casing, links 105 operatively connecting the cover and container, and a stop pressed inwardly from the rear wall of said casing positively limiting the rise of said container and opening of said cover.

6. A desk appliance comprising a base, a casing fixed thereon, a cover hingedly engaged on said casing, a card container movable up and down in said casing, straight 115 links operatively connecting the cover and container, a fixed stop in said casing to positively limit raising said container, and a spring detent to engage said container when in its highest position, said detent also retaining the cover in an open position.

7. A desk appliance comprising a raised hollow base having ornamental flanged edges and containing a plurality of prong-receiving openings in its upper surface, integral strengthening ribs on said base, a tray having prongs secured in certain of the base openings and containing prong-receiving openings near its ends, and brackets at the ends of said tray, said brackets having prongs to engage in the openings in said tray and other prongs to engage in certain of the openings in said base.

8. A desk appliance comprising a raised sheet metal base containing a plurality of prong receiving openings, a hollow casing

composed of a rear wall, side walls and sectional front wall, a panel removably engaged between the sections of said front wall level therewith, prongs on the lower edges of said rear wall and panel respectively, 20 said prongs being secured in the openings in said base, a flanged cover hinged to fold over said casing, a card container slidable vertically in said casing, operative connections between said cover and container, and 25 means for arresting and retaining said receiver when at its highest point.

This specification signed this 24th day of September, 1925.

WILLIAM C. HIERING.
